DESIGN FOR A CEILING LAMP

Hilyard R. Robinson, Washington, D. C., and
Aksel J. C. Knudstrup, Vienna, Va.

Application August 3, 1938, Serial No. 79,070

Term of patent 7 years

To all whom it may concern:

Be it known that we, Hilyard R. Robinson and Aksel J. C. Knudstrup, citizens of the United States, residing at Washington, District of Columbia, and Vienna, county of Fairfax and State of Virginia, have invented a new, original, and ornamental Design for a Ceiling Lamp, of which the following is a specification, reference being had to the accompanying drawing, forming a part thereof.

In the drawing:

Figure 1 is a side elevational view of a ceiling lamp, showing our design,

Figure 2 is a bottom plan of the lamp, and

Figure 3 is a vertical sectional view partly broken away and on a slightly reduced scale of the reflector portion of the lamp.

The dominant features of the design are shown in solid lines in the drawing.

We claim:

The ornamental design for a ceiling lamp, as shown and described.
